EXPLOSIVE ACTUATED PIN DRIVER

Alfred Wolf, Basel, Switzerland, assignor to Societe de Prospection d'Inventions Techniques Spitz, Bourg-Les-Valence (Drome), France, a corporation of France
Original application Aug. 21, 1957, Ser. No. 679,450.
Divided and this application Mar. 6, 1961, Ser. No. 102,341

Claims priority, application Switzerland Aug. 25, 1956
2 Claims. (Cl. 1—44.5)

This application is a divisional application of application Serial No. 679,450 filed August 21, 1957.

It is well known practice to use a pin designed to be driven, under the action of a gas-pressure, into hard material (such as wood, cement, concrete, etc.), and a firing apparatus to do so, the barrel of which, at the rear end of the bore, is joined, through a shoulder, to a loading chamber which is, on the rear, obturated by a cap which comprises a guide for the firing pin of the propulsive charge which is to fire the pin.

In known devices of this type, there is, in the loading chamber, a cylindrically shaped cartridge holder, in the axial hole of which the cartridge is engaged. After each firing, the cap is removed and the cartridge holder is taken out of the loading chamber, and the cartridge case is ejected out of the holder, by means of a rod acting from the front.

However, such ejection of the cartridge cases often results in difficulties, because, if the cartridge holder is not perfectly clean, the case jams, due to the action of the explosion pressure.

Even when the cartridge holder is made of appropriate steel, difficulties appear after a rather short use, and lead to trouble in service. On the other hand, when the pin is fired, a part of the exploding gases escape through the space between the cartridge holder and the loading chamber, and reach the space situated behind the cap of the firing device. Aside from the dirtying of parts which thus occurs, and which leads to trouble in use, the resulting loss of pressure in the barrel lowers the power of ejection of the pin from the barrel. Similar insufficiencies result from the loss of gases which, in known devices, occurs as a part of the gases passes between the wall of the bore and the pin. The total loss of gases, at rear and front, is such that the pin is driven into the material (which it has to penetrate) with a power considerably and undeterminably lower than its pre-determined value.

The object of the present invention is to obviate to the above drawbacks. It covers, on the one hand, a pin-ammunition unit, in which the pin is designed to be driven, under gas pressure, into hard materials, and, on the other hand, a device of the above mentioned type, for firing such pins, said unit being characterized by the fact that it comprises a block made of distortable material, having, on the one hand, a rear part shaped to correspond to the shape of the loading chamber, an annular shoulder designed to come into contact with the shoulder of the rear end of the barrel, and an axial cavity designed to receive the propulsive charge, which is closed at the rear by the holder of the primer, and on the other hand, a front part forming a wad, comprising a guiding surface which corresponds to the bore of the barrel and presents, towards the front, a lodging into which is forced the rear end of the pin, to which the said front part serves as centering means, the bottom of the axial cavity being level with the shoulder, in such a way that the pressure of the gases produced by ignition of the charge, entails, on the one hand, under the action of expansion, a gas-tight closing of the rear part of block against the wall of the loading chamber and, on the other hand, the shearing, driving back, and expulsion of the front part of the block

2

which serves as guide to the pin, as well as gas-proof tightening of this part of the block against the wall of the bore.

It is not absolutely necessary that the charge should be contained in a cartridge, and therefore that the block should act only as a cartridge holder, since there is no reason why the charge could not be directly lodged in the axial cavity of the rear part of the block, this cavity being obturated by the part supporting the primer. However, even if a cartridge is used, no trouble can occur when the case of the cartridge is ejected, since the cartridge holding block is used only once, and the fresh ammunition which replaces it is in the form of another cartridge ready for use and lodged in such a block.

15 The said block may be made of any distortable material answering to requirements, preferably, of course, some cheap and easily workable material. The power of explosion to which the block is submitted being rather high, there is no need of imposing high distortability characteristics, so that the block may be made of material neither particularly elastic nor adhesive, such as are, for instance, the known polyamides. For example, hard rubber may be used, or various synthetic products, particularly synthetic resins (cellulose acetate).

20 25 On the annexed drawing, some examples of embodiment of the invention are disclosed.

FIG. 1 is a section view of one embodiment, the parts being ready for firing.

30 FIG. 2 is a view similar to the first one, disclosing the various parts after firing.

FIGS. 3 and 4 are similar views showing two different embodiments of the ammunition holding block.

In FIG. 1, the firing device comprises a barrel 1, the rear end of which has a cylindrical widening 2, behind 35 which is situated the cylindrical loading chamber 3. The latter is provided in a part of the body 4 of the firing device, this part having, at its rear end, a thread upon which is screwed an obturating cap 5 provided with corresponding threads. This part has an axial hole in which 40 is guided the firing pin 6. The rear end of the firing pin 6 protrudes from the obturating cap 5, and is subjected to the action of a known device, herein not represented, by means of which the firing pin is driven forward when the shot is fired.

45 In the firing position disclosed in FIG. 1, the pin 7, of a conventional type, is in axial position in the rear part of the bore 8. It is held, at its rear end, by a block B of distortable material, the front part 9 of which presents a guiding surface 10 corresponding to the calibre of the bore and serving as centering means. The rear part 11 of the block is shaped to correspond to the contour of the loading chamber 3. Therefore, it has, in its part adjacent to the front part 9, an annular surface in close contact with the shoulder 12 through which the barrel is joining, towards the rear end of the bore 8, with the cylindrical wall of the chamber 3. In the rear part 11 is, moreover, provided a central cylindrical cavity 13, which opens to the rear. In this cavity, which is substantially level with the shoulder 12, is lodged a cartridge 14 which contains the charge of powder dosed in a convenient way, the bottom of the cartridge 14 containing the primer, being placed in the cavity and obturating it towards the rear.

50 55 60 65 The barrel 1 is mounted in such a way that, after removal of the cap 5, it can be axially slid through the chamber 3, driving positively the block, while it cannot slide towards the front, this being prevented by shoulder 15 of the body 4, the front face of the widening 2 bearing against said shoulder 15.

70 The front part 9 of the block B is designed to constitute an axial projection of the rear part 11, this projection

having a cylindrical recess 16, open towards the front, in which is engaged the rear end of the pin 7, which is threaded. Said recess may be provided with a thread corresponding to that of the pin, so that the pin may be screwed onto it and unscrewed. However, practically, it is sufficient to give to this recess 16 the shape of a cylindrical hole, or of a slightly truncated cone, in which the rear end of the pin may be engaged. Further, of course, the rear end of the pin may be embedded in part 9.

When the shot is fired, by driving forward the firing pin 6, the pressure produced in the cartridge 14, which propagates in the cavity 13, and which is rather high, results, as shown in FIG. 2, in a barrel shape swelling of the wall 17 of the cartridge and of the rear part 11 of the block B, until close contact is obtained with the wall of the chamber 3, this contact being close enough to be gas-tight. Moreover, the gas pressure produces a sudden separation of the front part 9 from the rear part 11 of the block, in the point of the lesser resistance, as it is indicated by the breaking surface 18 shown in FIG. 2. This is accompanied by the expulsion of the front part 9 which guides the pin. Said front part 9, expands, due to the inertia, until it is gas-tightly pressed against the wall of the bore 8, forming thus a wad. The cavity 19 which receives the gases produced by the explosion, behind the front part 9 of the block B, is thus hermetically obturated, towards the front as well as towards the rear, so that, without any loss of pressure, the whole volume of gas produced by explosion can act upon the pin and drive it with a well determined force out of the barrel.

The recoil produced by the expulsion of the pin 7 with the front part 9 of block B is transmitted to the firing device, being however, distributed, for the main part, directly over the body 4, with a frictionally adhering action, due to the tightness hereinabove mentioned, of the rear part 11 of the block B against the wall of the chamber 3, and for the remainder, over the obturating cap 5. Thus, there is practically no transmission of the recoil to the threaded link between the cap 5 and the body 4, which is a particularly desirable feature.

After completion of the firing, the cap 5 is unscrewed from the threaded body 4. The barrel 1 is then taken out, by sliding it rearwards in the body 4, thus pushing out of the loading chamber 3 the rear part 11 of the block situated in said loading chamber.

It is to be noted that the bottom of the cavity 13 of the block B is slightly on the downstream side with respect to the shoulder 12. This particularity is very important, because when the block B is put in place in the firing device, it presents the lower resistance section at the level of the shoulder 12, in such a way that when the shot is fired, there will remain practically nothing of the front part 9 of the block B within the barrel.

This feature facilitates the ejection of the rear part 11 of this block.

After the barrel has been pushed forward, a new pin with a loaded block has been pushed in the loading chamber, and the cap 5 has been screwed on, the device is ready for another shot.

The embodiment of the block shown in FIG. 3 differs from that shown in FIG. 1 only by the fact that the charge of powder 20 is directly in the cavity of the rear part 11 of the block B, and that this cavity is closed by a disc 21 provided with the primer, the edge 22 of this disc being forced into an annular groove provided close to the edge of the cavity, in the wall of the latter. The disc 21 has, consequently, the same function as the bottom of the cartridge, in the embodiment shown in FIG. 1, which bottom, in as much as it acts as support for the primer, obturates the rear part of the cavity.

The embodiment of the block shown in FIG. 4 differs from that of FIG. 1 only by the fact that the rear part 11a of the block Ba has the shape of a truncated cone 23, the narrow part of which is directed towards the front. In this case, the wall of the loading chamber provided in the body 4, must have a corresponding truncated cone shape. This truncated cone presents, however, at the point where it is joined with the front part 9, also an annular surface 24, which, when the device is loaded, comes into contact with the shoulder through which the barrel, at the rear end of the bore, is joined with the loading chamber. This shoulder is, then, because of its conical shape, smaller than the shoulder 12 of the embodiment shown in FIG. 1.

What I claim is:

1. In a firing device for driving pins into hard material under gas pressure comprising a body provided with a bore, said body being provided at the rear end with a cavity coaxial with said bore, said bore opening into said cavity, a rear obturating member detachably securable in the outer end of said cavity, said cavity being of larger diameter than said bore to define a shoulder therewith at their junction, said cavity providing a chamber to receive an ammunition unit carrying the pin, a barrel positioned in said bore for sliding movement relative to said body, said barrel having a rear enlarged portion adapted to move in said cavity, said portion having a shoulder adapted to abut said first shoulder, said barrel, when actuated rearwardly following detachment of the obturating member, providing ejection of the spent ammunition unit from the cavity.

2. A firing device as claimed in claim 1, wherein the barrel has a front part which protrudes from said body, so that said barrel may be driven by its front part into said body for ejecting, by its rear part, said spent ammunition out of the cavity.
